UNITED STATES PATENT OFFICE.

FREDERICK HAROLD NIES, OF BROOKLYN, NEW YORK.

ARTIFICIAL DENTURE.

Application filed March 17, 1924. Serial No. 699,923.

This invention relates to artificial dentures and aims to provide certain improvements therein.

The invention is particularly directed to dentures in which the artificial teeth are connected with the plate at their basal portions. The plate is usually of rubber, vulcanite, celluloid, or other material which is moldable, and the teeth are united thereto usually by some sort of an anchor connected with the tooth which is molded into the plate. Various forms of anchor have been used with more or less satisfactory results, but each of these with which I am acquainted has some disadvantage which interferes with a perfect and durable union between the plate and teeth of the required strength to withstand the strains of use.

According to the present invention I provide a tooth having an elongated recess or deep socket at its basal end, and within this socket is arranged a tubular anchor post having at its protruding end a flange which preferably is adapted to be spaced apart from the base of the tooth. Preferably the flange is originally formed on the post, but it is permissible to slit the ends of the post in such fashion that the sections thus formed may be turned down at an angle to the post to form the flange. In any event, by preference the flange is slit so as to provide a number of sections, some of which may be turned down at a more acute angle with relation to the post body in order that they may rest on the end of the tooth and thus insure that the flange of the post is sufficiently separated from the end. Other features of improvement are provided which will be hereinafter more fully described.

Referring to the drawings which illustrate several forms of the invention:

Figure 1 represents a longitudinal section of a tooth showing the improved post in perspective.

Fig. 2 represents a similar section with the post in diametrical section showing the use of the bent down flanges.

Fig. 3 is a section similar to Fig. 2 illustrating the post with a solid or unsplit flange before any portion of it has been bent out of the general plane.

Fig. 4 is a top view of the preferred form of post.

Fig. 5 is a section of a modified form of post.

Referring to the drawings, let A indicate

an artificial tooth of the type described, that is to say, one in which the tooth is united to the plate B by contact with the basal end C of the tooth. The latter is usually formed slightly concave so that the vulcanite or other material of which the plate is composed enters the basal end of the tooth and makes a sort of mortise connection therewith. D is the improved post provided by the present invention, which post comprises a cylinder or tube of any desired cross section, it being preferred to make the tube in one piece by the drawing process. However, the post may be rolled or may consist of two longitudinal sections.

The basal end of the post is provided with a flange E which may be continuous as illustrated in Fig. 3, or may be slotted or slit as illustrated in Figs. 1 and 2. I prefer the latter construction since it permits some of the sections F to be bent downwardly below their fellows G so that they contact with the basal end of the tooth, and thus hold the end of the post with the sections G sufficiently spaced from the end of the tooth to permit the flow of rubber or vulcanite beneath the sections F and G, particularly the latter. This obviates the necessity of accurate proportioning of the depth of the socket H with reference to the length of the post, it being only necessary to form the socket in excess of a given depth.

In lieu of forming the head or flange initially on the post, the latter may be split longitudinally and the sections thus formed bent down to form the flange.

In Fig. 5 I have shown a construction in which the post is formed of sheet metal and has two legs J, K originally lying flat with the head L. These are afterwards bent inwardly and then downwardly so as to constitute in effect a tubular post. The lower end of the post may be flared outwardly in this, or in the other constructions illustrated, if desired in order to secure a better binding effect between the tooth and post, although this will not ordinarily be necessary.

Preferably slots I will be provided at the incisal end of the post so as to better permit the flow of rubber in the socket of the tube and to aid in the strength of the union between the post and the tooth. Flange E of the post is preferably made of such material that it can be readily bent so that even

in the continuous form one edge of the flange can be bent inwardly to contact with some portion of the tooth structure. It will be understood that the basal ends of the 5 teeth are customarily ground or hollowed out so that a portion of the flange will strike the tooth wall and hold the post in its upward position with a large part of the flange spaced apart from the tooth. So also it is 10 possible to bend a portion of the flange to secure the same results. It is also possible in some cases to permit the flange to rest on the base of the tooth without separation therefrom. It is also permissible to bend 15 the flange to a position more or less in parallelism with the basal end of the tooth. These and similar structures are intended to be covered by the appended claims.

The use of a tubular post is very advantageous in that when the post is applied to the tooth the rubber or cementitious material is placed in the tooth and the post pressed down without forcing out any considerable amount of the material and that 25 which does flow out being permitted to do so by the hollow construction of the post. In the use of solid posts the post acts as a piston and squeezes down the material in the socket which opposes the proper seating 30 of the post. On occasions also, it puts such a pressure on the tooth as to split the latter. When the post of the present invention is inserted in the tooth, the material flows easily through one side to the other, 35 or out through the center of the post, and the latter may be accurately adjusted in position and holds its place firmly when so adjusted. A post of the present invention is very cheap and simple to manufacture, 40 and lends itself readily not only to the initial formation of the denture, but also to replacement of individual teeth where the latter may become damaged in use.

While I have shown and described the 45 preferred embodiment of my invention I do not wish to be limited thereto, since various changes may be made therein without departing from the spirit of the invention.

What I claim is:

50 1. A post for artificial teeth, comprising a substantially tubular member adapted to enter a socket in the tooth, said tubular member having near its outer end a transversely extending part adapted to project beyond the base of the tooth so as to permit the material of the plate to pass beneath it whereby such part becomes embedded in the plate, and forms an anchorage for the tooth, a portion of such transversely extending 55 means being adapted to hold the post with a portion of such part separated from the base of the tooth.

60 2. A post for artificial teeth comprising a substantially tubular member adapted to enter a socket in the tooth, and having a 65

flange adapted to project above the basal end of the tooth for embedment in the plate, said flange being formed in a number of sections at least one of which sections is adapted to be bent out of the general plane of the flange to support the post on the tooth.

3. A post for artificial teeth comprising a substantially tubular member adapted to enter a socket in the tooth, and having a flange adapted to project above the basal 75 end of the tooth for embedment in the plate, said flange being formed in a number of sections at least one of which sections is adapted to be bent out of the general plane of the flange to support the post on the tooth, and said post having at its inner end a communicating passage between its inner and outer sides.

4. An artificial denture comprising one or 85 more teeth and a plate with an anchorage comprising a tubular post, a socket in the tooth into which said post projects, and a flange at the upper part of the post separated at least in part from the basal end of the tooth.

5. An artificial denture comprising one or more teeth and a plate with an anchorage comprising a tubular post, a socket in the tooth into which said post projects, a flange at the top of the post separated from the basal end of the tooth, and said flange having a plurality of sections, some of which are bent downwardly to contact with the basal end of the tooth.

6. A post for artificial teeth comprising 100 a member adapted to enter a socket in the tooth, said member being tubular whereby to permit flow of the material of the plate into it, and having a flange at its top adapted to project above the basal end of the tooth 105 so that its under side is separated therefrom at least in part whereby to permit passage of the material of the plate beneath said flange, and said flange being bendable so that a part thereof may be bent so as to contact with the basal end of the tooth and thus maintain the post with a part of the flange above said basal end.

7. A post for artificial teeth comprising a substantially tubular member adapted to enter a socket in the tooth and having a flange at its outer end, with means carried by the outer end of said member for separating the post from the tooth, with at least a part of said flange projecting beyond and spaced apart from the basal end of the tooth so as to permit passage of material beneath said flange.

8. An artificial denture comprising a tooth and a plate with an anchorage comprising a tubular post and a socket in the tooth into which said post projects, and a flange at the top of the post, the flange and tooth being so constructed as to maintain a part of the flange spaced apart from the 125 130

basal end of the tooth, and the plate material passing around and beneath said flange.

9. A post for artificial teeth comprising a member adapted to enter a socket in the tooth and having a flange at its outer end, with means carried by the outer end of said member for separating the post from the tooth, with at least a part of said flange projecting beyond and spaced apart from the basal end of the tooth so as to permit passage of material beneath said flange.

10. A post for artificial teeth comprising a member adapted to enter a socket in the tooth and having formed integrally therewith a flange at its outer end, with means carried by the outer end of said member for separating the post from the tooth, with at least a part of said flange projecting beyond and spaced apart from the basal end of the tooth so as to permit passage of material beneath said flange.

11. A post for artificial teeth comprising a substantially tubular member open at both ends and adapted to enter a socket in the tooth, said member having a flange at its outer end, with means carried by the outer end of said member for separating the post from the tooth, with at least a part of said flange projecting beyond and spaced apart

from the basal end of the tooth so as to permit passage of material beneath said flange.

12. A post for artificial teeth comprising a member adapted to enter a socket in the tooth and having bendable spacing means carried by the outer end of said member adapted to longitudinally adjust the position of said post with respect to the tooth.

13. A post for artificial teeth comprising a substantially tubular member adapted to enter a socket in the tooth, said tubular member having means adapted to engage a wall of the tooth other than the bottom of said socket for holding the top of the post at least partially separated from the tooth and the upper part of the tubular member having transversely extending portions to form an anchorage with a plate, the construction being such that the material of the plate is permitted to flow around the transversely extending portion of the post into the socket, and the post having a clear passage through it from top to bottom so that the material of the plate may flow through the top of the post into the interior of the post.

In witness whereof, I have hereunto signed my name.

FREDERICK HAROLD NIES.
